TEACHING AID FOR DEMONSTRATING PRINCIPLES OF PHYSICS

John Lawlor, Tappan, N.Y., and John Sgombick, Ramsey,
N.J., assignors to Xerox Corporation, Stamford, Conn.

Filed Dec. 26, 1972, Ser. No. 318,311

Term of patent 14 years

Int. Cl. D19—07

U.S. Cl. D19—62

FIG. 1

FIG. 2

FIG. 3

FIG. 4

FIG. 5

FIG. 6

FIG. 7

FIG. 1 is a perspective view of the teaching aid for demonstrating principles of physics;

FIG. 2 is a rear view of the teaching aid for demonstrating principles of physics;

FIG. 3 is a bottom view of the teaching aid for demonstrating principles of physics;

FIG. 4 is a top view of the teaching aid for demonstrating principles of physics;

FIG. 5 is a left side view of the teaching aid for demonstrating principles of physics;

FIG. 6 is a front view of the teaching aid for demonstrating principles of physics;

FIG. 7 is a right side view of the teaching aid for demonstrating principles of physics.

We claim:

The ornamental design of a teaching aid for demonstrating principles of physics, substantially as shown.
